COVER DRAPE FOR BATHTUBS

Elsie B. Rindt, Milwaukee, Wis.

Application August 23, 1948, Serial No. 148,261

Term of patent 14 years

(Cl. D4—2)

To all whom it may concern:

Be it known that I, Elsie B. Rindt, a citizen of the United States, and resident of Milwaukee, in the county of Milwaukee and State of Wisconsin, have invented a new, original, and ornamental Design for a Cover Drape for Bath Tubs, of which the following is a specification, reference being had to the accompanying drawing, forming part thereof.

Fig. 1 represents a front perspective view of my new cover drape for bath tubs, or the like; and

Fig. 2 is a rear perspective view of the same.

I claim:

The ornamental design for a cover drape for bath tubs, as shown.

ELsie B. RINDT.
